INVENTOR

BY *Victor J. Evans*

UNITED STATES PATENT OFFICE.

WILLIAM E. JONES, OF WHITE, ARKANSAS, ASSIGNOR OF ONE-HALF TO FRANK SATURLY CANNON, OF CROSSETT, ARKANSAS.

LATCH.

Application filed June 3, 1925. Serial No. 34,662.

To all whom it may concern:

Be it known that I, WILLIAM E. JONES, a citizen of the United States, residing at White, in the county of Ashley and State of Arkansas, have invented new and useful Improvements in Latches, of which the following is a specification.

This invention relates to improvements in latches for doors and the like, the general object of the invention being to provide a simple lock which can be easily moved to open position by a knob or the like at either side of the door or barrier and which is provided with a thumb latch for locking it in closed position when the barrier is to be locked from the inside.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view showing the latch in use.

Figure 2 is a section on line 2—2 of Figure 1.

Figure 3 is an end view.

In these views, A indicates the barrier and B a part of the frame. The latch bar is shown at 1 and is pivoted to a bracket 2 which is fastened to the barrier and which has its outer end passing through a slot in the outwardly extending flange of an angle plate 3 which is fastened to an edge of the barrier. This slot forms a guide for the latch bar. The keeper plate 4 is adjustably fastened to the frame B by means of the screws 5 which pass through the slots 6. This plate has an outwardly extending flange 7 which has a beveled end 8 and a notch 10 in said end serves as a keeper notch for the end of the latch bar 1. A spring arm 11 has one end fastened to the bracket 2 and its free end is slotted to receive the bar 1 so that this spring arm acts to hold the latch bar in latching position. A stem 12 is rotatably carried by the door and is provided with the knobs or handles 13 so that it can be turned. A slotted arm

14 is fastened to the stem and the bar 1 passes through the slot therein. Thus when the stem is turned, the arm is moved, and this movement of the arm will swing the bar 1 on its pivot and against the action of its spring 11 and move the end of the bar out of the keeper notch 10. When the knob or handle is released, the spring 11 will return the parts to latching position.

The ends of the handles may be provided with radium carrying parts 15 so that the knobs or handles can be readily grasped at night.

A thumb latch 16 is adjustably pivoted to the flange 7 by means of a pin 17 passing through a slot 18 in the latch and the beveled point 19 of said latch is adapted to engage a beveled edge on the bar 1, when the latch is swung into latching position by its handle 20 so as to hold the bar in locking position.

This latch is for doors and especially for night latches; the thumb latch being pivotally mounted and when in locked position, hangs over the center of gravity and is pointed to hook over the latch bar in such a manner as to draw closer to keeper plate and hold latch bar more securely the more pressure is brought to bear against it.

This latch is very strong, operates smoothly, and when thumb latch is off, can be opened with equal ease from either side of the door.

It is more simple than door locks, less liable to break, easily mounted on doors and with radium buttons and finger knobs placed so as to protect against jambing and breaking, making it quickly seen in the dark. All parts are reversible to suit doors swinging opposite ways, with the exception of the keeper.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A latch of the class described comprising a latch bar, a keeper member having a notch therein for receiving the end of the bar, a slotted guide for the bar, a spring for holding the bar in latching position, a knob stem, an arm thereon having a slot

therein for receiving the bar, and a thumb latch on the keeper member for locking the bar in latching position.

2. In combination with a barrier and its frame, a latch bar pivoted to the barrier, a slotted plate on the barrier forming a guide for the outer end of the latch bar, a spring for holding the bar in latching position, a keeper plate having an outwardly extending flange, one end of which is beveled and

slotted to engage the outer end of the latching bar, a knob stem passing through the barrier, an arm on the stem having a slot therein through which the latch bar passes, a handle on each end of the stem and a thumb latch pivoted to the flange of the keeper plate for locking the bar in latching position.

In testimony whereof I affix my signature.

WILLIAM E. JONES.
